CLAIM

The ornamental design for a cross bottomed magnetic light source attachment, as shown and described.

DESCRIPTION

FIG. 1 is a top plan view of a cross bottomed magnetic light source attachment showing my new design;

FIG. 2 is a bottom elevational view thereof;

FIG. 3 is a side elevational view thereof;

FIG. 4 is a side elevational view thereof;

FIG. 5 is a top and side perspective view thereof; and,

FIG. 6 is a bottom and side perspective view thereof.

The broken lines shown in the drawings are for illustrative purposes only and do not form part of the claimed design.
